UNITED STATES PATENT OFFICE.

CHARLES S. MEYERS, OF SHARPSBURG, PENNSYLVANIA.

CAR-FENDER.

SPECIFICATION forming part of Letters Patent No. 586,449, dated July 18, 1897.

Application filed January 27, 1897. Serial No. 620,894. (No model.)

To all whom it may concern:

Be it known that I, CHARLES S. MEYERS, a citizen of the United States of America, residing at Sharpsburg, in the county of Allegheny 5 and State of Pennsylvania, have invented certain new and useful Improvements in Car-Fenders, of which the following is a specification, reference being had therein to the accompanying drawings.

10 This invention relates to certain new and useful improvements in car-fenders, and has for its object to provide a fender designed principally for use on street-cars and the like that will fold in such a manner when it strikes 15 an object as to prevent the object from falling from the fender and coming in contact with the wheels, as is often the case.

The invention has for its further object to provide means whereby this action in the 20 fender is accomplished by the object coming in contact with the fender or rather through the object being lifted onto the fender; furthermore, to construct a fender that will be extremely simple in its construction, strong, 25 durable, effectual in its operation, and comparatively inexpensive to manufacture.

With the above and other objects in view the invention finally consists in the novel construction, combination, and arrangement 30 of parts to be hereinafter more specifically described, and particularly pointed out in the claims.

In describing the invention in detail reference is had to the accompanying drawings, 35 forming a part of this specification, and wherein like letters of reference indicate similar parts throughout the several views, in which—

Figure 1 is a perspective view of my improved fender, showing same in position on the car and in the lowered position. Fig. 2 is a front elevation of the same. Fig. 3 is a side elevation of the fender in the folded position. Fig. 4 is a side view of the holding- 40 ratchet, showing a portion of the car. Fig. 5 is a perspective view of the block carrying the spring. Fig. 6 is a side view of one of the supporting rods or braces. Fig. 7 is a perspective view of the ratchet side brace. Fig. 8 is a front plan view of the top supporting-bar. Fig. 9 is a perspective view of the 45 connecting-beam.

Referring now to the drawings by reference-letters, *a* indicates the side braces of the lower fender, which are curved upwardly at 55 their rear ends and pivotally connected to the curved vertical braces or supports *b*, said supports *b* being in turn pivotally connected at their upper ends to lugs *c* *c*, secured on the guides *d* *d*, and extending from said guides 60 is a cross-brace *e*, extending across the front of the car and carrying pawl *f* to engage the ratchet *g*, pivotally supported in lugs *h* *h*, attached to the front of the car and provided with a downwardly-extending arm *k*, pivoted 65 to a crank or beam *l*, which is in turn pivotally supported in lugs *m* *m*, secured to the front of the car.

Pivotally connected to the side braces *a* *a* is an elbow-lever *n*, to the rear end of which 70 is pivotally connected a vertical brace *o*, attached at its upper end to the guide *d*. Said elbow-lever is fulcrumed to the angle-brace *p*, provided in the vertical portion thereof with a slot *q* and on one of its engaging faces 75 with a rack *r*, adapted to engage a spur-gear *s*, carried by a rod *t*, extending transversely of the car and provided on each end with cranks *u* *u* to elevate the fender, as will be more fully explained hereinafter. A rod *v* 80 extends vertically at the front of the car at each side, and operating on this rod is a block *a*, recessed to receive a spring *b*', encircling the rod and resting at its lower end on the guides *d* *d*, attached to said blocks *a*', and to 85 the upper ends of the angle-brace *p* is a brace *c*', pivotally secured to the block *a*' and at its lower end to the rack-bar *p*. The fender is provided with a suitable netting formed in three sections *D*' *E*' *F*', attached to the braces 90 *a* and *b*, as is fully shown in Fig. 2 of the drawings.

Describing the action of the fender briefly, the same is as follows: We will assume that the car is moving in the position shown in Figs. 1 95 and 2, and that a person or object is struck by the front portion of the fender, which engages the person or object and carries same up onto the netting, where it strikes the beam or elbow-lever *l*, and through this medium releases the 100 ratchet *g* from its engagement with the bar *f*, thus through the action of the spring *b*' forcing down the rear portion of the fender slightly and which depresses the brace *o* and one arm

of the beam n , elevating the other arm, which is pivotally connected to the side braces a , bringing the front portion of the fender to the position shown in Fig. 3, which prevents the object from rolling off the fender. To return the fender to its normal position, the same is set by hand by pulling the forward portion of the fender down into the former position, or, in other words, to the position shown in Figs. 1 and 2.

In case it is desired to elevate the fender sufficiently to permit of the coupling of two cars together the cranks $u u$ are turned, which causes the spur-gears $s s$ to engage in the racks $r r$ and thus elevate the slotted angle-braces, and through this medium and the braces c to elevate the fender sufficiently to permit the coupling to be made.

By means of the ratchet in the brace p the fender may be set at any desired height from the track, and in order for the motorman to release the rack g from its engagement with the plate f I have provided near the upper end of this rack a pin g' , passing through the front of the car and encircled by a spring h' . By simply pulling on this pin the motorman brings the rack g out of engagement with the plate, and the fender may then be elevated or lowered, as may be desired. This rack g may also be operated by downwardly-extending arms $k' k'$ (shown in Fig. 9 of the drawings) and adapted to be engaged by the object or person and release the rack g in the same manner as heretofore described for the beam l , as by reason of the upper netting being attached at its upper end to a cross-rod l' , which engages the arms $k' k'$, and in case the object should fail to engage the beam or crank l the depressing of this netting by rea-

son of the object coming in contact with the same would operate these arms and release the rack from its engagement with bar f , and thus allow the same operation as hereinbefore stated.

Having thus described my invention, what I claim as new, and desire to secure by Letters Patent, is—

1. In a car-fender, the side braces a , carrying a suitable netting, curved vertical braces b , pivotally attached to said side braces a , an elbow-lever n , pivotally connected thereto and fulcrumed to the angle-braces p , single brace o , connected to said elbow-levers, a cross-brace l , extending above the fender and bearing against the spring b' , a rack g pivotally supported on the front of the car, said rack engaging a pawl f , carried by the cross-brace, and means for elevating the front portion of the fender when the object comes in contact therewith, substantially as shown and described.

2. In a car-fender composed of different sections, a suitable covering for each section, vertical curved braces, slotted side rods p , to which said elbow-levers are pivoted, a cross-brace carrying a bar and downwardly-extending arms, sliding blocks carried by vertical rods and connecting said blocks with said slotted side rods, said slotted rods having a rack therein to engage a spur-gear carried by a rod extending transversely of the car, substantially as shown and described.

In testimony whereof I affix my signature in presence of two witnesses.

CHARLES S. MEYERS.
